LOCOMOTIVE STOKER

Charles J. Surdy, Tuckahoe, N. Y., assignor to
The Standard Stoker Company, Incorporated,
a corporation of Delaware

Application October 31, 1935, Serial No. 47,547

16 Claims. (Cl. 198—15)

My present invention relates to locomotive stokers and particularly to means for transferring fuel from the tender to the locomotive.

By this invention I seek to improve the transfer of fuel from the tender to the fuel distributing means on the locomotive and to increase the water capacity of the tender. These results I have attained by a novel relation and arrangement of the fuel transferring means, and the attainment 10 of such results constitutes the main object of my invention.

Another object of my invention is the provision in a locomotive and tender of a flexible fuel transferring means having a conveyor member on the tender mounted for movement about a horizontal transverse axis, and during which movement the axis of said conveyor member is maintained in the same vertical plane.

A further object of this invention is the provision in a locomotive and tender of a fuel transferring means comprising a conveyor member on the locomotive, a conveyor member on the tender mounted for longitudinal movement with respect thereto and being also mounted for movement about an axis extending transversely of the tender, means for preventing lateral movement of the conveyor member, and an intermediate conveyor member at one end universally connected to one of said conveyor members and being flexibly connected to the other of said conveyor members for lateral movement only with respect thereto.

A still further object resides in the provision, in the structure above set forth, of means supporting said intermediate conveyor member between the ends thereof.

As a more specific object, a resilient support is contemplated for the intermediate conveyor member of this invention.

Other objects, advantages and novel features of construction will become apparent upon reading the following specification in connection with the drawings, in which,

Fig. 1 is a vertical medial section through adjacent portions of a locomotive and tender, showing the stoker according to my invention in similar section;

Fig. 2 is a plan view taken on the line 2—2 of Fig. 1;

Figs. 3 and 4 are sectional views taken on the lines 3—3 and 4—4 respectively, of Fig. 1;

Fig. 5 is a view similar to a portion of Fig. 1 illustrating a modification of my invention; and

Fig. 6 is a sectional view taken on the line 6—6 of Fig. 5.

55 In the preferred form of my invention as illus-

trated in Figs. 1 to 4 inclusive, A is the locomotive, B the tender and C a member for intercoupling the locomotive and tender. The locomotive includes the usual boiler firebox 10 having a firing opening 11 in the backwall 12. On the tender there is the usual fuel bin 13 disposed above the floor 14 which is provided with an aperture 15 for receiving shiftable plates 16. Below the floor 14, the tender is provided with a compartment 17 formed by side plates 18 and the rear plate 19, which plates constitute walls of the water compartment 20.

The stoker S consists of a fuel distributor 21 disposed at the firing opening 11 and the means for transferring fuel from the bin 13 to said fuel distributor 21 for distribution over the firebed. Comprising this transferring means, which is indicated generally by T, is a conveyor member 22 mounted on the locomotive, a conveyor member 23 mounted on the tender, and an intermediate 20 conveyor member 24 disposed between the first and second named conveyor members. These conveyor members are in novel relation with each other and with the intercoupled locomotive and tender, as will presently appear.

The conveyor member 23, which is mounted within the compartment 17, includes a trough conduit 25 underlying the fuel bin 13 and arranged to receive fuel through the aperture 15 in the floor 14. A screw conveyor 26 is mounted 30 within the trough conduit 25 and is operatively connected at its rearward end with gearing 27. A prime mover 28 supplies the motive power for driving said gearing 27 through the intermediacy of shafting 29. At its rearward end, the trough 35 conduit 25 is provided with a pair of transversely spaced rollers 30, each of which is journaled upon a trunnion 31 extending in a horizontal direction transversely of the tender. Beneath each roller 30 is a rail or runway 32 upon which the roller 30 is 40 adapted to move fore and aft and also to pivot about a horizontal axis.

While providing for this motion of the trough conduit 25, I utilize means for preventing lateral movement of such conduit. This means consists 45 of a pair of spaced rollers 33 at each upper side of the trough conduit 25 and which rollers are each mounted upon a vertically disposed pin 34. The rollers 33 are adapted to fit between the wear plates 35 which are secured to each side plate 18 50 of the compartment 17 so as to roll freely therealong while preventing an appreciable lateral movement of the trough conduit 25.

The conveyor member 22 of the locomotive includes a conduit 36 which supports the distributor 55

21 and communicates with the lower portion of the firing opening 11. A firedoor 37 closes the upper portion of the firing opening. At its lower end, the conduit 36 is provided with a foot member 38 which is secured to a bracket 39 for rigidly attaching the conduit 36 to the locomotive.

As stated heretofore, the intermediate conveyor member 24 is disposed between the conveyor members 22, 23 and consists of a tubular conduit 10 40 which is inextensible in length. At its rearward end the tubular conduit 40 is provided with a spherical shell 41 arranged to be received by a complementary spherical seat 42 formed with the forward end of the trough conduit 25. The 15 spherical shell 41 and the spherical seat 42 together cooperate as a universal joint 43 between the trough conduit 25 and the tubular conduit 40.

The forward end 44 of the tubular conduit 40 is seated in the lower rearward portion 45 of the 20 conduit 36 and is mounted for movement with respect to said conduit 36 about an upstanding axis only. To provide for this movement, the forward end 44 of the tubular conduit 40 is provided on its under side with a circular lug 46 which fits within the circular recess 47 formed in the lower rearward portion 45 of the conduit 36. A conveyor screw 48 is mounted within the tubular conduit 40 and it is flexibly connected at 49 to the trough screw 26. The forward end of 30 this conveyor screw 48 is tapered and extends beyond the forward end of the tubular conduit 40 and into the conduit 36 so as to terminate closely adjacent the forward wall 50 thereof.

Since the tubular conduit 40 at its rearward 35 end is universally connected to the trough conduit 25, which latter is free to move up or down upon the rollers 30, additional means are provided for supporting the tubular conduit 40 and maintaining its vertical relation with respect to said conduit 36. This means consists of a roller 51 which is journaled upon a pin 52 carried by the tubular conduit 40 intermediate the ends thereof and disposed longitudinally of the locomotive. The roller 51 is adapted to roll along the upper surface 53 of the bracket 54 which is carried by the locomotive frame 55.

It will be apparent from Figs. 1 to 4 inclusive, that all lateral movement of the transferring means incidental to operation of the locomotive and tender around a curve is assumed solely by the intermediate conveyor member 24. The slight vertical movement of the transferring means occasioned during passage of the locomotive and tender over switches, turntables and frogs is assumed solely by the universal connection 43 between the trough conduit 25 and the tubular conduit 40.

By the construction illustrated, it will be apparent that the compartment 17 which receives the stoker conveyor member 23 may be relatively narrow since means are provided for preventing any lateral swinging movement thereof. By using a compartment of comparatively narrow width, the water capacity of the tender tank is increased. Furthermore, since the transferring system is inextensible in length, and also because vertical movement between the conveyor members 23 and 24 is prevented by the lug 46, the forward end of the conveyor screw 48 may be positioned closely adjacent the forward wall 50 of the conduit 36. It is also apparent that this conveyor screw 48 may extend into the conduit 36 for a considerable distance thereby rendering 75 more positive delivery of fuel to the distributor

21 than has been heretofore possible in stokers of similar construction.

In the modification illustrated in Figs. 5 and 6, the relation of the intermediate conveyor member 24a with the conveyor members 22a and 23a is reversed from that illustrated in the preferred embodiment of my invention. Thus, the forward end of the tubular conduit 40a is provided with a spherical ball element 60 which is received in a spherical seat 61 formed at the lower end of the conduit 36a to form a universal joint 62 between the tubular conduit 40a and the conduit 36a. At its rearward end the tubular conduit 40a is provided with an upstanding circular lug 63 arranged to fit into a circular recess 64 in the cover 65 which fits over the rearward end of the conduit 40a and is secured to the forward end of the trough conduit 25a.

By this relation of parts, the intermediate conveyor 20 24a is always in the same vertical relation with the conveyor member 23a. Additional supporting means may also be provided for the intermediate conveyor member 24a. In this form the support bracket 66 is secured to the tender frame 67 and is provided with an upper surface 25 68 over which a support 69, carried by the intermediate conveyor member 24a, is adapted to slide. Due to the fact that the conveyor member 22a is mounted on the locomotive in precisely the same manner as the conveyor member 22 of the preferred form of my invention, the intermediate conveyor member 24a will have a slight vertical movement with respect to the locomotive and tender when these vehicles pass over switches, turntables and frogs. For this reason, 35 the support 69 should be made of spring steel so that it will be capable of flexure in a vertical direction in order to assure that it will function as a support for the intermediate conveyor member 40a under all conditions of service.

As in the preferred form of this invention, the intermediate conveyor member 24a, by reason of its relation with the conveyor members 22a and 23a, will provide the necessary flexibility in the transferring means when the locomotive and tender are negotiating curves. This form differs from the construction illustrated in the preferred form in that the universal joint 62 between the tubular conduit 40a and the conduit 36a provides for the flexibility in the transferring 50 means when the locomotive and tender are at different elevations with respect to each other, such as in crossing switches and turntables. Because of the vertical movement between the conduit 36a and the intermediate conduit 40a, the 55 forward end of the conveyor screw 48a should be spaced slightly from the forward wall 50a of the conduit 36a.

From the foregoing, those familiar with the art will understand that by the present invention I have increased the water capacity of the tender and that I have improved the means for transferring fuel from the tender to the distributor on the locomotive by a novel relation of parts as set forth in the appended claims.

I claim:

1. In an intercoupled locomotive and tender, means for transferring fuel from the tender to said locomotive comprising a conveyor member mounted on the tender for movement fore and aft with respect thereto, said conveyor member being also mounted for movement about an axis extending transversely of the tender, means preventing movement of said conveyor member laterally with respect to said tender, a conveyor

means for transferring fuel from the tender to said locomotive comprising a conveyor member mounted on the tender for movement fore and aft with respect thereto, said conveyor member being also mounted for movement about an axis extending transversely of the tender, means preventing movement of said conveyor member laterally with respect to said tender, a conveyor member mounted on the locomotive, and an intermediate conveyor member at one end being universally connected to the conveyor member on said locomotive, said intermediate conveyor member at its opposite end being flexibly connected to the conveyor member on said tender for lateral movement only with respect thereto.

11. In an intercoupled locomotive and tender, means for transferring fuel from the tender to said locomotive comprising a conveyor member mounted on the tender for movement fore and aft with respect thereto, said conveyor member being also mounted for movement about an axis extending transversely of the tender, means preventing movement of said conveyor member laterally with respect to said tender, a conveyor member mounted on the locomotive, an intermediate conveyor member at one end being universally connected to the conveyor member on said locomotive, said intermediate conveyor member at its opposite end being flexibly connected to the conveyor member on said tender for lateral movement only with respect thereto, and means supporting said intermediate conveyor between the ends thereof.

12. In an intercoupled locomotive and tender, means for transferring fuel from the tender to said locomotive comprising a conveyor member mounted on the tender for movement fore and aft with respect thereto, said conveyor member being also mounted for movement about an axis extending transversely of the tender, means preventing movement of said conveyor member laterally with respect to said tender, a conveyor member mounted on the locomotive, an intermediate conveyor member at one end being universally connected to the conveyor member on said locomotive, said intermediate conveyor member at its opposite end being flexibly connected to the conveyor member on said tender for lateral movement only with respect thereto, and resilient means supporting said intermediate conveyor between the ends thereof.

13. In an intercoupled locomotive and tender, means for transferring fuel from the tender to said locomotive comprising a conveyor member mounted on the tender for movement fore and aft with respect thereto, said conveyor member being also mounted for movement about an axis extending transversely of the tender, means preventing movement of said conveyor member lat-

erally with respect to said tender, a conveyor member mounted on the locomotive, an intermediate conveyor member at one end being universally connected to the conveyor member on said locomotive, said intermediate conveyor member at its opposite end being flexibly connected to the conveyor member on said tender for lateral movement only with respect thereto, and means between the ends of said intermediate conveyor member supporting it on the tender.

14. In an intercoupled locomotive and tender, means for transferring fuel from the tender to said locomotive comprising a conveyor member mounted on the tender for movement fore and aft with respect thereto, said conveyor member being also mounted for movement about an axis extending transversely of the tender, means preventing movement of said conveyor member laterally with respect to said tender, a conveyor member mounted on the locomotive, an intermediate conveyor member at one end being universally connected to the conveyor member on said locomotive, said intermediate conveyor member at its opposite end being flexibly connected to the conveyor member on said tender for lateral movement only with respect thereto, and resilient means between the ends of said intermediate conveyor member supporting it on the tender.

15. In an intercoupled locomotive and tender, means for transferring fuel from the tender to the locomotive comprising a conveyor member mounted on one of said intercoupled vehicles for movement about an axis extending transversely of such vehicle, means preventing movement of said conveyor member laterally with respect to the vehicle upon which it is mounted, a conveyor member mounted on the other of said intercoupled vehicles, and an intermediate conveyor member at one end being universally connected to one of said conveyor members, said intermediate conveyor member at its opposite end being flexibly connected to the other of said conveyor members for lateral movement only with respect thereto.

16. In an intercoupled locomotive and tender, means for transferring fuel from the tender to said locomotive comprising a conveyor member mounted on the tender for movement about an axis extending transversely of the tender, means preventing movement of said conveyor member laterally with respect to said tender, a conveyor member mounted on the locomotive, and an intermediate conveyor member at one end being universally connected to one of said conveyor members, said intermediate conveyor at its opposite end being flexibly connected to the other of said conveyor members for lateral movement only with respect thereto.

CHARLES J. SURDY.
